DESIGN FOR A TEXTILE FABRIC OR SIMILAR ARTICLE

Edmond P. Bixer, New York, N. Y.

Application April 24, 1940, Serial No. 91,917

Term of patent 3½ years

To all whom it may concern:

Be it known that I, Edmond P. Bixer, a citizen of the United States of America, residing at New York, in the county of New York and State of New York, have invented a new, original and ornamental design for a Textile Fabric or Similar Article, of which the following is a specification, reference being had to the accompanying drawing constituting a part thereof.

The figure is a plan view of a textile fabric showing my new design.

I claim:

The ornamental design for a textile fabric or similar article, as shown.

EDMOND P. BIXER.
